(57) **CLAIM**

The ornamental design for a boot, as shown and described.

DESCRIPTION

FIG. 1 is a perspective view of a boot showing my new design.

FIG. 2 is another perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof.

FIG. 9 is an enlarged view of the area labeled "9" in FIG. 1; and,

FIG. 10 is an enlarged view of the area labeled "10" in FIG. 3.

The dash-dash broken lines illustrate portions of a boot that form no part of the claimed design. The dot-dash broken lines show an area of enlargement and the dot-dash lines form no part of the claimed design.

1 Claim, 10 Drawing Sheets
